UNITED STATES PATENT OFFICE.

ERASTUS E. WINKLEY, OF LYNN, MASSACHUSETTS.

MACHINE FOR FEEDING TOGETHER THE MARGINAL PORTIONS OF THIN FLEXIBLE FABRIC OR OTHER SHEET MATERIAL.

1,158,763.

Specification of Letters Patent.

Patented Nov. 2, 1915.

Application filed August 3, 1910. Serial No. 575,324.

To all whom it may concern:

Be it known that I, ERASTUS E. WINKLEY, a citizen of the United States, residing at Lynn, in the county of Essex and State of Massachusetts, have invented certain new and useful Improvements in Machines for Feeding Together the Marginal Portions of Thin Flexible Fabric or other Sheet Material; and I do hereby declare the following to be a full, clear, and exact description of the invention, such as will enable others skilled in the art to which it appertains to make and use the same.

This invention relates to machines for feeding together the marginal portions of thin flexible fabric, or other sheet material.

In making articles where a plurality of pieces of sheet material are to be secured together and incorporated into the construction, it is desirable in some instances to place the sheets in a position so that their edges abut and secure them together by applying to the marginal portions of the sheets, over the meeting edges, a stay strip, or welting.

In other instances it is desirable to place the sheets in layers with their edges in alignment, or, if a felled seam is to be used, with the marginal portion of one sheet projecting beyond the other. It is often desirable, also, to secure one sheet to another by overlapping their marginal portions. In all of the above referred to arrangements of the sheets and in others which will readily occur to those skilled in the arts to which this invention appertains, it is desirable that the proper relative position of the edges of the sheets be accurately predetermined, and thereafter maintained throughout the securing operation.

The object of the present invention is to enable thin flexible fabric, or other sheet material, to be properly positioned for securing together the edges of the sheets in a desired relation and thereafter held in such position while being secured, no matter what particular arrangement of the sheets is selected. It is desirable that the work positioning devices be arranged to operate on the sheets in advance of the securing means and that while the work positioning devices are operating at one point the securing means are operating concurrently at another point on a portion of the work already positioned.

In accordance with this object the features of the invention may be generally described

as comprising gages for the edges of the sheets having a fixed relation to each other and to the mechanism or devices for fastening the sheets together, means for engaging the sheets and feeding their edges into engagement with the gages to place them in fastener receiving position, and preferably means to prevent the sheets from wrinkling or buckling as they are fed to the gages. Separate means may be employed to feed the work through the machine, but this is not essential.

For convenience of illustration the invention has been shown as applied to one of the well known types of dry thread sewing machine but it should be distinctly understood that the invention, except as specifically recited in certain of the claims, is not limited to the use of a stitch to fasten the sheets together as the inventor contemplates the use of any convenient and appropriate fastening means after the edges of the sheets have been properly positioned for the securing operation.

In the illustrated embodiment of the invention, which in its general construction and features is typical of a machine for obtaining the results referred to, the edge gages for the sheets are fixed relatively to the needle and in such relation to each other as to cause the edges of the sheets to be aligned. A work table is provided on which the sheets rest, and work-positioning presser feet above and below the table, one for each sheet, operate to cause the sheets to engage their respective edge gages. These feet operate through slots in protective plates lying in planes parallel to the surface of the work table and extending over the sheets in such contiguity thereto as to prevent their wrinkling, or buckling, as they are fed inward to the gages. While not essential, it is preferred that the work-positioning presser feet be utilized as work feeding devices, and when so utilized the protective plates may conveniently be arranged to assist in feeding the work. In the illustrated embodiment of the invention this arrangement is used.

These and other features of the invention, including certain details of construction and combinations of parts, as will readily be understood by those skilled in the art, will be further explained in the following description and then pointed out in the appended claims.

With these generally stated facts in view.

the aims and objects of the present invention will best be made clear from a description of the accompanying drawings showing one form of means for carrying it into practical effect, in which—

- 5 Figure 1 is a front elevation of a common form of dry thread sewing machine having the present invention embodied therein, certain parts being shown in section; Fig. 2 is a perspective detail showing the relation of the edge gages, presser feet, and needle; Figs. 3, 4 and 5 are sections, respectively, on the lines 3—3, 4—4, and 5—5 on Fig. 1; Fig. 6 is a section of the arm substantially on the line 6—6, Fig. 1; Fig. 7 shows the upper presser foot slide as viewed from the left of Fig. 1; Fig. 8 is a detail view of the feeding device; Fig. 9 is a detail view of the feed slide; Figs. 10, 10^a and 10^b are diagrammatic views of a modification of the present invention for uniting two pieces of fabric in a lap joint which will be hereinafter described; Figs. 11, 11^a, 11^b and 11^c are similar views of the invention as adapted to unite two pieces of fabric by a felled seam, which will be described in detail.

The sewing machine shown in Fig. 1 may be of any convenient form having a work table 1, an arm 2, an upper driving shaft 3 having a pulley 300 driven from a suitable source of power, and a lower shaft 4, such as, for example, the well known Wheeler & Wilson single thread chain-stitch sewing machine. In the illustrated embodiment of the invention showing the present improvements, there are indicated a needle 5 (Fig. 1), carried by a needle bar operated as usual by the shaft 3 and a looping hook 6 operated through suitable connections from the shaft 4. A slide 7, one portion of which is flush with the top of the work table, is mounted in ways on the table 1 and adapted to move in the line of the stitches. Vertically mounted in the slide is a bar 8 having on its upper end a plate 9 overlying the slide 7 and extending to the left of the path of the needle. A similar bar 10, likewise mounted in the slide, carries a plate 11 overlying the plate 9, both bars being held yieldingly downward by springs 12, 12 and collars 13, 13.

The plate 9 has a gage or shoulder 14 forming an abutment for the edge of a lower piece of fabric 15, the upper plate 11 also having a gage or shoulder 16, in this case in vertical alinement with the shoulder 14, forming an abutment for the edge of an upper fabric 17. The plate 11 has a slot 18 for the passage of the needle. A slot 19 in the plate 9 must extend from the rear edge to the center, as the fabric above and below

this plate will be united by a stitch which must pass from the slot to the rear with the feed of the cloth.

It is now desirable to provide means to place the edges of the two fabrics in contact with the shoulders above described and to hold them in this position, while a stitch is being formed. For this purpose there is provided an upper presser foot 20 which engages the fabric 17 through an extension of the slot 18 in the plate 11 and a lower presser foot 21 to engage the fabric 15 through a slot 22 in the slide 7.

The presser foot 20 is carried by a presser foot slide 23 (Figs. 1 and 7) and slotted at its upper end to receive a spring 24 which tends to force the presser foot downward and at certain times to cause it to engage the fabric 17 as shown in Fig. 4. The presser foot slide 23 has formed integral therewith, an arm 25 adapted to slide in ways in a block 26. A slide 27 is fixed to the block 26 and engaged in ways 28 formed on the bottom of the arm 25 extending at right angles to its length. Thus the presser foot 20 is capable of movement in three directions; vertically in the slide 23, laterally by means of the arm 25 in its ways, and in the line of the stitches by means of the slide 27 and ways 28. A spring 29, surrounding a stud 30 mounted in the arm 25, having a seat at one end on a lug projecting from the block 26 and at the other against suitable check nuts on said stud, urges the arm 25, and therefore the presser foot, to the right in Fig. 1. A lever 31, pivoted at 32 to the arm 2, has one end bearing against the stud 30 and the other in operative relation to a cam 33 on the shaft 3.

The arm 25 carries a shoulder screw 34 having pivoted thereon a lever 35, one end of which extends below a pin 36 fixed to the presser foot 20, the presser foot slide being slotted at 36^a for said pin. The other end of the lever 35 underlies a vertical plunger 37 (Fig. 6), mounted in suitable ways on the arm 2. Projecting from the plunger 37 is an arm 38 having a cam roll adapted to cooperate with the cam 39 carried by the shaft 3. A spring 40 extends from the lever 35 to the arm 2, keeping the cam roll on the arm 38 in contact with its cam 39. It is now apparent that rotation of the cam 39 will act through the plunger 37 to depress one end of the lever 35, elevating the other end and the pin 36, thereby raising the presser foot from contact with the fabric 17, as is best shown in Figs. 1, 6 and 7.

As has been stated, it is desirable to engage the fabric by means, in part, of the presser foot described above, in advance of the stitch forming means, to bring the edges into the desired relation with one another and then holding the edges thus positioned to bring them to the needle. This movement

of the fabric will determine the length of the stitch and will constitute the feed of the sewing machine as shown in the present design, although it is possible for a skilled mechanic to construct a similar machine in which there will be more than one operation of the fastening device for each operation of the cloth positioning devices. To this end there is provided the following means:—A lever 41 is pivotally mounted at 42 to the lower portion of the arm 2, engaging at one end a pin 43 secured to the block 26 and at the other end engaging a pin in the end of an arm 44 secured to the top of a rock shaft 45. In order that the travel of the positioning devices (or the length of the stitch) may be varied, the pivot 42 is mounted in a slot running lengthwise of the arm 2 and also in a slot in the lever 41 (see Fig. 6). These slots are not, however, shown as the adjustments described are common and well known to those skilled in the art. Thus by adjusting the pivot 42 in said slots the leverage may be changed, the motion of the rock shaft remaining the same. The rock shaft 45 is mounted in bearings in the upright portion of the arm 2 and has at its lower end a bell-crank 46, the long arm of which is given a reciprocating motion by the cam 47 on the shaft 4, a plan of which is shown in Fig. 8. The short arm of the bell-crank is operatively connected to a lever 48 pivoted at 49 below the work table 1. The other end of the lever 48 is engaged between two lugs 50 on the slide 7. The pivot 49 is adjustable in a similar manner to the upper pivot 42 whereby the travel of the slide 7 may be made to correspond to the travel of the upper presser foot and connecting parts.

The lower presser foot 21 is mounted to slide vertically in a block 51 supported by ways 52 in the slide 7. A spring 53 forces the presser foot 21 upward and, unless prevented, against the fabric 15. The block 51 is held toward the needle or to the right in Fig. 1 by a spring 54 compressed by an arm 55 projecting from the slide 7. Depending from the table 1 is a part 56 (Fig. 4) which affords a support for a screw 57 which carries a lever 58. One end of this lever has a cam roll in engagement with a face cam path 59 of a cam 60. The other end of the lever 58 is in contact with one of the sides of the block 51 whereby upon rotation of the cam 60, the undulation of the cam path 59 is transmitted to the block 51 as a reciprocating motion identical with the motion imparted to the presser foot 20 by the cam 33. As the block 51 carries the presser foot 21, it is evident that the two presser feet will move in unison in both directions in the plane of the table 1.

It is desirable that the presser foot 21 be forced downward against the spring 52 and away from the fabric 15, simultaneously

with the lifting of the presser foot 20 from its fabric. To this end there is projecting from the presser foot 21 a pin 61 adapted to be engaged by a lever 62 pivoted at 63 to the part 56. The opposite end of this lever is operated through a cam roll in the cam path 63^a, shown in dotted lines in Fig. 4, to depress, at times, the presser foot 21.

Referring to Figs. 1, 2 and 3, the plates 9 and 11 are provided with certain lifting devices which will be described whereby these plates are, at suitable times, lifted to allow movement of the fabrics held between them. On a rod 64, supported by the depending part 56 and a like part 65, are pivoted two levers 66 and 67 which are operated through proper cam rolls engaged in the cam paths 69 and 68 in the cam 70 to lift the bars 8 and 10. It is desired that the plates 9 and 11 shall lift a predetermined distance each time irrespective of the positions from which they start. As shown in Fig. 1, the plate 9 is urged by the spring 12 to grip the fabric between itself and the upper surface of the slide 7, likewise the plate 11 tends to press the fabric upon the plate 9. The material to be operated upon will vary in thickness in different places, thereby leaving the plates at different heights above the work table. At the time when the presser feet are to act to push the two fabrics against their respective shoulders 14 and 16 on said plates, it is necessary that the spring pressure of these plates be relieved but the plates should be lifted but slightly lest the action of the presser feet cause wrinkles in the fabric. This position is shown in Fig. 4, the lift given the plates being exaggerated that it may be observable. To this end there are provided two wedges 71 (Fig. 3) interposed between the lower ends of the bars 8 and 10 and their levers 66 and 67. Said wedges are pivoted to two bell-cranks 72 which are pivoted in turn at 73 to suitable supports depending from the table 1. The horizontal arms of the bell-cranks are acted upon by two flat springs 74 fixed to the table 1, normally tending to thrust the wedges 71 to the left in Fig. 3 until further motion is prevented by the wedges contacting with their respective bars. Fig. 3 shows the cam rolls controlling the levers 66 and 67 on a slight rise 75 in the cam paths which, as the wedges 71 are advanced, will lift the bars 8 and 10, and therefore the plates 9 and 11, a slight distance that the fabric may be adjusted. It will be observed that the rises in the cam path 68 are slightly greater than those of the path 69 which is necessary as the plate 11 controlled by the cam path 68 must be lifted enough to give clearance to the upper fabric 17 plus the clearance given the lower fabric 15.

Before relieving the plates for positioning

the fabric, they must be allowed to grip the material or to measure it, so that they may be lifted a proper distance from its surface which is slightly variable. For this purpose 5 there is a short drop at 76 in the cam paths 68 and 69 which will lower the working ends of the levers 66 and 67. At this time the wedges 71 are withdrawn by means of a pin 77 (see Fig. 5) in the end of a lever 78 pivoted at 79 to the table 1. A roll 80 mounted 10 on the lever 78 is adapted to bear upon the surface of a cam 81 which at various times operates the pin 77, through the connections described, to contact with the short arms of the levers 72 and thereby retract the wedges 71. The rise 82 on the cam 80 is timed to operate at the same time as the drop 75 on the cam 70 thereby retracting the wedges while the plates are lowered by the co-acting 15 cams and under spring tension downward. The wedges 71 are immediately allowed to advance again by the cam 81 to the position shown in Fig. 5, which corresponds to the position shown in Fig. 3.

20 As the cam 70 continues its rotation with the arrow in Fig. 3, the long dwell in the cam paths 68 and 69 will allow the plates 9 and 11 to engage their respective fabrics during which time the slide 7 and the block 25 30 35 40 45 are actuated, as has been described, to advance the plates and presser feet from their cloth positioning location, shown in Fig. 4, into line with the needle which is the feed of the machine. Continuing the rotation of the cam 70, a rise 83 comes into operative position. This rise is greater than the rise 75 which will give considerable greater lift to the plates 9 and 11, the wedges 71 having been advanced at the start of this rise by a suitable drop on the cam 81. At this time the presser feet and plates are moved from in line with the needle back to the position shown in Fig. 4, the fabric being held from retraction by the needle which is in the work at this time.

The operation of the embodiment of the invention now described may be briefly stated as follows:—The plates and presser feet move to the front of the machine, the presser feet position the work, and the plates and presser feet return to their first position where the stitch is formed. For convenience in giving a detailed description, the various movements will be given serial numbers in the order of the time of their occurrence in the cycle of this machine but it should be understood that some of the movements extend during other movements and in some cases the exact time is immaterial and so the time given herein is arbitrarily chosen and in all cases the given sequence is capable of wide variation.

Assume that the needle 5 is about to enter the fabric to form a stitch. The plates 9 and 11 are holding the work in the position

in which it has been placed by a previous cycle of the machine. The movements will be described with reference to Fig. 1, that is, looking at the front of the machine. First. Needle penetrates work to form stitch. Second. Presser feet move to the left under the action of their respective cams 33 and 59. At the same time the presser feet are lifted from contact with the fabric by the cams 39 and 60. Third. The wedges 71 are allowed to move to operative position by the cam 81, as shown in Figs. 3 and 5. Fourth. The plates 9 and 11 are lifted by the rises 83 on the cam 70. Fifth. The plates and presser feet move to the front of the machine by the connections described from the cam 47 and rock shaft 45 into line with the position of the next stitch to be formed. The fabric is at this time held in fixed position by the needle and the plates are separated to give clearance to the work. Sixth. The plates are lowered at the point 76 on the cam 70 and simultaneously the wedges 71 are withdrawn at the point 82 on the cam 81. The plates are now gripping the fabrics between each other and the upper surface of the slide 7 under the action of the springs 12. Seventh. The wedges are immediately advanced to operative position and the plates lifted by the rise 75 on the cam 70. As has been stated, this rise is comparatively slight, the object being to relieve the gripping effect of the springs 12 a sufficient amount to allow the fabric to be moved between the plates but not enough to permit the fabric to wrinkle. Eighth. The presser feet are spring-pressed against the fabrics, the lifting action of the cams 60 and 39 having ended. At about the same time the springs 29 and 54 are permitted to act by the cams 59 and 33 whereby the fabrics are forced to the right until further movement in this direction is prevented by the shoulders 14 and 16. The presser feet may remain in the position defined by the shoulders or they may slip over the fabric from this point, depending on the relative strengths of the springs and the nature of the fabric. Ninth. The plates are again permitted to grip the fabrics by means of their operating cams and the withdrawal of the wedges 71. The needle has now completed its stitch and is withdrawn from the work. Tenth. The needle now being clear of the work the cam 47 operates through its connections to move the plates toward the rear of the machine. This movement will of necessity advance the fabric into line with the needle in position to receive another stitch. The cycle of the machine is now repeated.

It is evident that this invention may be embodied in various forms in which tacks, rivets, cement, stitches, or other devices, may be used as the securing means. A few variations are shown in the drawings in which

a stitch forming mechanism is indicated as the securing means.

Fig. 10 shows an isometric view of the essential parts of this invention adapted to join two pieces of cloth in a lap joint, as shown in Fig. 10^b. In this form there is a work table 100 having a ledge 101 projecting slightly less than the thickness of the cloth. A plate 102, slotted at 103 for the passage of the needle and stitches, is fixed to a bar 104 which is capable of vertical movement. An upper plate 105 fixed to a similar bar 106 overlies one end of the plate 102 and has one edge in vertical alinement with one side of a ledge 107. Both plates are slotted at 108 for the passage of two presser feet 109. A needle 110, operated in the usual manner in connection with stitch forming means, is adapted to pass through the plates and secure together the fabric held between them. Fig. 10^a is a section approximately in the line of the presser feet 109 and shows two pieces of fabric inserted in proper relation. As is plain from this figure, if the presser feet are spring-pressed toward one another, the fabrics will be brought into engagement with the two ledges 107 and 101, the plates 102 and 105 being operated in proper time to engage and release the fabric as has been described in the preferred form. In this form there is no feeding means shown which is unnecessary, as any usual sewing machine feed can be readily adapted thereto.

Fig. 11 shows an embodiment of the invention as used to join two fabrics by a tape overlaying the butted edges, known as a welted seam, which is shown in Fig. 11^b. In this arrangement there is a plate 112 carried on a bar 113 slotted for the reception of two presser feet 114. A work table 115 has a very thin ledge 116 adapted to engage one edge of each piece of fabric on each side thereof. Fig. 11^a is a front view of Fig. 11 and shows the fabrics in engagement with said ledge. A double needle stitch forming device is used, the two needles 117 being an equal distance each side of the ledge. Fig. 11^c, a section on the line of the ledge 116, shows the relation of the parts described. A suitable feeding device, as indicated at 118, may be provided to advance the cloth. A tape or welt *w* is drawn from a source of supply through a slot 119 and secured to the two fabrics, as shown in the drawings. The vertical movement of the plate 112 and the action of the presser feet 114 to position the fabrics against the ledge 116 will be evident without further description when taken in connection with the foregoing detailed description of the preferred form.

A third variation is shown for making a felled seam. This is done in two operations, the first by means of the plates 120 and 121, having gages or shoulders for the fabrics,

respectively, at 122 and 123. This form is identical with that described in the preferred form and similarly shown in Fig. 2, with the exception that the shoulders 122 and 123 are not in vertical alinement which will produce, when the work is spread, the joint or seam shown in Fig. 12^a.

The fabric is presented in this condition to the action of a feller 124 attached to a presser foot bar 125. The lower surface 126 of the feller, shown in Fig. 12^c, (a section on the line 12^c on Fig. 12^b) is actuated in the same manner as has been described with respect to the cloth engaging plates. A presser foot 127 engages the cloth from below and feeds it at right angles to the line of the stitches until the shoulder formed by the seam, shown in Fig. 12^a, is engaged by the vertical wall 128. In this manner the position of the upper fabric is determined with respect to the lower and the felling stitches are applied at a constant distance from the edge of the lower fabric. The feller, being old in the art, is not described, being assumed that the reader is familiar with its usual mode of operation.

With the aid of the drawings and descriptions of these three modifications and of the preferred form of this invention, a skilled machine designer will be enabled to build those forms described and others which the work to be performed may demand, the construction being limited only by the claims.

While there have been shown details of mechanical devices which have been found well adapted to carry the invention into effect, it is to be understood that said invention is not restricted or circumscribed thereby, being defined in the claims by intentionally broad language comprehensive of various forms or embodiments of the invention.

What is claimed as new, is:—

1. A machine for fastening together sheets of material, having, in combination, means for inserting fastenings to fasten the sheets together, gages, means acting independently of the movement of the sheets past the fastener inserting means for feeding the sheets to bring their edges into engagement with the gages to place the sheets in fastener receiving positions, and means for preventing the sheets from wrinkling or buckling as they are fed to the gages.

2. A machine for fastening together sheets of material, having, in combination, means for inserting fastenings to fasten the sheets together, means acting independently of the movement of the sheets past the fastener inserting means for feeding the sheets to bring their edges into predetermined relation as they are presented to the fastener inserting means, and means for preventing the sheets from wrinkling or buckling as they are fed by the said feeding means.

3. A machine for inserting fastenings in

- a sheet of material, having, in combination, fastener inserting means, a gage for the edge of the sheet to position the sheet relatively to said means, and a combined feeding and 5 positioning presser foot acting on the face of the sheet to feed the sheet and hold its edge against the gage.
4. A machine for inserting fastenings in a sheet of material, having, in combination, 10 fastener inserting means, a gage for engagement with the edge of the sheet to position the sheet relatively to said means, a presser foot for engagement with the face of the sheet, and means to move the presser foot 15 both in the direction of and transverse to the line in which the sheet is fed past the fastener inserting means.
5. A sewing machine for stitching one or more sheets of material, having, in combination, 20 stitch forming mechanism, a gage for the edge of a sheet of material, means acting independently of the movement of the sheet past the stitch forming mechanism for feeding the sheet toward the edge gage, and 25 means for preventing the sheet from wrinkling or buckling as it is fed.
6. A sewing machine for stitching together sheets of material, having, in combination, 30 stitch forming mechanism, gaging means for the edges of the sheets, sheet feeding means comprising devices acting independently of the feed movement of the work past the stitch forming mechanism for maintaining the edges of the sheets in engagement with 35 the gaging means as the sheets are fed, and means for preventing the sheets from wrinkling or buckling during their feed movement.
7. A sewing machine for stitching together 40 sheets of material, having, in combination, stitch forming mechanism means acting independently of the feed movement of the work past the stitch forming mechanism for positioning the edges of the sheets in a pre- 45 determined relation before they are presented to the stitch forming mechanism, and means acting to prevent the wrinkling or buckling of the sheets as they are positioned.
8. A machine for inserting fastenings in 50 a sheet of material, having, in combination, a gage for the edge of the sheet, plates for engagement with the opposite faces of the sheet, means for feeding the sheet to bring its edge into engagement with the gage, and 55 means for separating the plates to permit the sheet to be fed by the said feeding means, the plates acting to prevent the sheet from wrinkling or buckling as it is fed.
9. A machine for inserting fastenings in
- a sheet of material, having, in combination, 60 fastener inserting means, a gage for the edge of the sheet, plates for engagement with the opposite faces of the sheet, means for feeding the sheet to bring its edge into engagement with the gage, means for separating the plates to permit the sheet to be fed by the said feeding means, the plates acting to prevent the sheet from wrinkling or buckling as it is fed, and means for moving one of the plates with the sheet as the 70 sheet is fed past the fastener, inserting means.
10. A machine for inserting fastenings in a sheet of material, having, in combination, 75 fastener inserting means, a gage for the edge of the sheet, plates for engagement with the opposite faces of the sheet, means for feeding the sheet to bring its edge into engagement with the gage, means for separating the plates to permit the sheet to be fed by the said feeding means, the plates acting to prevent the sheet from wrinkling or buckling as it is fed, means acting to maintain the plates in gripping relation 80 with the sheet as it is fed past the fastener, inserting means, and means for moving the plates in a direction to carry the sheet past the fastener inserting means while the plates are maintained in gripping relation there- 85 with.
11. A machine for inserting fastenings in a sheet of material, having, in combination, 90 a gage for the edge of the sheet, plates for engagement with the opposite faces of the sheet, means for feeding the sheet to bring its edge into engagement with the gage, and means acting to move the plates relatively a substantially uniform distance regardless of the thickness of the sheet to separate the plates and thereby permit the sheet to be fed 100 by the said feeding means, the plates acting to prevent the sheet from wrinkling or buckling as it is fed.
12. A machine for inserting fastenings in 105 sheets of material, having, in combination, fastener inserting means, gages for the edges of the sheets, plates for engagement with the opposite faces of each sheet, means for feeding the sheets to bring their edges into engagement with the gages, and means for separating the plates to permit the sheets to be fed by the said feeding means, the plates acting to prevent the sheets from wrinkling or buckling as they are fed.

ERASTUS E. WINKLEY.
